TELEPHONE HANDSET SUPPORT

Harry W. McCune, Indianapolis, Ind., assignor to Bell Telephone Laboratories, Incorporated, Berkeley
Heights, N.J., a corporation of New York

Filed Dec. 6, 1966, Ser. No. 4,927

Term of patent 14 years

(Cl. D26—14)

FIG. 1 is a front view of a telephone handset support showing my new design, the rear view being substantially a mirror image thereof;

FIG. 2 is a side view of the telephone handset support, the opposite side being substantially a mirror image thereof; and

FIG. 3 is a top view of the telephone handset support.

The dominant features of my design reside in the portions shown in full lines.

I claim:

The ornamental design for a telephone handset support, substantially as shown and described.
